[57] CLAIM

The ornamental design for a case for a video recorder, as shown and described.

DESCRIPTION

FIG. 1 is a front perspective view of a case for a video recorder showing my new design;
FIG. 2 is a left side elevational view thereof;
FIG. 3 is a rear elevational view thereof with an intermediate portion of the carrying strap broken away and omitted for ease of illustration;
FIG. 4 is a top plan view thereof; and
FIG. 5 is a bottom plan view thereof.
